UNITED STATES PATENT OFFICE

148,718

DESIGN FOR AN ASH TRAY AND COASTER
COMBINATION

Edward R. Peterson, Rockford, Ill.

Application July 26, 1946, Serial No. 131,959

Term of patent 3½ years

(Cl. D85—2)

To all whom it may concern:

Be it known that I, Edward R. Peterson, a citizen of the United States, residing at Rockford, in the county of Winnebago and State of Illinois, have invented a new, original, and ornamental Design for an Ash Tray and Coaster Combination, of which the following is a specification, reference being had to the accompanying drawing, forming part thereof.

In the drawing:

Figure 1 is a perspective side view of an ash tray and coaster combination showing my new design;

Figure 2 is a side elevation thereof, and
Figure 3 is an end elevation thereof.

I claim:

The ornamental design for an ash tray and coaster combination, substantially as shown.

EDWARD R. PETERSON.
